UNITED STATES PATENT OFFICE

HENRI L. MARINDIN, OF WATERTOWN, CONNECTICUT, ASSIGNOR, BY MESNE ASSIGNMENTS, TO MOTO METER GAUGE & EQUIPMENT CORPORATION, OF LONG ISLAND CITY, NEW YORK, A CORPORATION OF DELAWARE

SIGNAL HORN

Application filed December 3, 1927. Serial No. 237,377.

This invention relates to acoustical signalling devices such for example as warning horns used on vehicles and boats, and has among its objects the provision of an improved durable construction for the desired purposes which will give a suitable warning signal, the intensity and characteristics of which may be accurately controlled.

Various other specific objects, features and advantages will more clearly appear from the detailed description given below, taken in connection with the accompanying drawings which form a part of this specification and illustrate, merely by way of example, one embodiment of the invention.

The invention consists in such novel features, arrangements and combinations as may be shown and described in connection with the device herein disclosed, by way of example, as illustrative of a preferred embodiment.

In the drawings, Fig. 1 is a side elevational view partly cut away of an electrically actuated horn embodying the invention;

Fig. 2 is a longitudinal sectional elevational view of a part of the horn shown in Fig. 1;

Fig. 3 is a transverse sectional elevational view taken substantially along line 3-3 of Fig. 2;

Fig. 4 is a perspective view of part of the electro-magnetic actuating device and connections which may be embodied in the horn as shown;

Fig. 5 is a plan view of a portion of the electro-magnetic structure such as used in the horn shown;

Fig. 6 is a sectional elevational view taken substantially along line 6-6 of Fig. 5 and showing additional parts in section; and

Fig. 7 is an enlarged detail view showing portions of the current interrupter device used in the horn.

The horn illustrated herewith is particularly adaptable for use on automobiles, motor boats or in other places where a dependable warning signal is desired which can be readily localized by the human ear and which at the same time will give a somewhat musical tone having pleasing characteristics in so

far as is consistent with giving an effective warning.

The structure may comprise a housing, as at 10, having a generally flat circular chamber 11 provided preferably with a single sound outlet, as at 12, in substantially direct air communication with the chamber spaces. The sound outlet may cooperate with conventional horn members as at 13.

Within the chamber 11 a pair of complementary vibratory members, comprising sheet metal discs or diaphragms 14 and 15, may be mounted in face to face relationship and secured together for substantially forming a complete enclosure for enveloping the operating parts. As indicated in Fig. 2, the discs 14 and 15 are preferably formed with concentric corrugations to increase their flexibility and also their desirable vibratory characteristics. The corrugations provide an effective increase in area of the diaphragms without enlarging the diameters thereof and furthermore permit the electro-magnetic actuating parts, rigidly mounted at the centers of the diaphragms as herein-after described, to move more freely back and forth without bending strains and thus also making possible a higher degree of perfection of operation of the current interrupter which is actuated conjointly by the two diaphragms, as hereinafter explained.

The peripheral edges of the discs as shown may comprise inwardly directed flange portions, as at 16, terminating in outwardly directed and abutting flange portions 17. Between the abutting flange portions 17, two or more layers of insulating material or gasket members, as at 18, may be placed. The flanges 17 may be secured together by a number of screws, as at 19, and/or by a number of supporting bolts, as at 20, passing through the walls at the periphery of the chamber 11, as best shown in Fig. 2. Suitable washer members 21 may be placed upon the bolts 20 to retain the supported vibratory members in the desired position substantially centrally of the chamber 11. The chamber 11 may be conveniently formed of two parts 22 and 23 slidably fitted at their peripheries at 24 and held together by the

bolts 20, some of which extend from the flanges 17 through the member 10, while others extend oppositely from the flanges 17 through member 11.

With the vibratory members supported as above described, the sound outlet 12 is in air communication not only with the vibratory disc 15 but also with the disc 14 by reason of the peripheral spaces, as at 25, extending around the flanges 17.

The electro-magnetic actuated means may comprise a pair of cooperating laminated core members 26 and 27 mounted respectively upon the vibratory discs 14 and 15. The arrangement of the laminations may be as indicated in Fig. 4, and the same may be rigidly secured to the vibratory discs as by a pair of angle strips, as at 28 and 29, embracing the laminations therebetween and having areas, as at 30, riveted through the vibratory discs. It will be observed that with this construction the edges of the laminations may be permitted to rest directly upon the vibratory discs, and if desired the discs may form a continuation of the magnetic path, and in any event the occurrence of air gaps of uncertain dimensions may be prevented between the discs and the laminations, thus insuring uniformity of the product essential for predetermined tone qualities.

At the center portions of the outside faces of the vibratory discs 14 and 15 rigid supplemental disc members, as at 31 and 32, may be riveted, the same rivets serving also to secure the angle strips 28 as above referred to. If desired, the disc 15 may be provided with a pair of superposed rigid discs 32 as shown. The disc 14 may be used to support certain interrupter and coil parts, as will be herein-after described. The discs 14 and 15 as weighted by the electro-magnetically operated parts at their centers become highly vibratory diaphragms which may be readily made with but slightly different characteristics. Such a pair of discs as at 32 offers one means of giving the disc 15 substantially the same frequency of vibration as the disc 14, compensating for the weight of the extra parts on disc 14. However, as a result of the small differences in shape and weight of the various small parts attached of these two diaphragms, a number of relatively musical overtones and some relatively sharp noises will be produced, giving a composite signal, the location of which is much more readily and quickly ascertained by the human ear than is the case with pure musical tones. The sounds thus produced are all combined and efficiently discharged through the single outlet 12, giving a very effective signal.

The electrical operating circuit may comprise an insulated binding post 33 extending through the walls of the chamber 11 to the flanges 17 and there brought into electrical contact with, and riveted through, a

strip of resilient conductive material 34, which is embraced between gasket members 18 and extends toward the center of the enclosure formed by the discs 14 and 15. At its inner end, the strip 34 may be provided with a nondeteriorating contact 35 for cooperation with a similar contact 36 supported upon a resilient conductive strip 37. The strip 37 may comprise one of a number of interrupter parts which are substantially rigidly secured, as by screws 38, to a lug 39, forming a part of one of the angle strips 28.

The resiliently supported cooperating contacts 35 and 36 provide a means for bringing the electric circuit connection from the non-vibrating parts of the device to the highly vibratory center portions but without the use of a continuous metallic conductor. It has been found that, especially with extensive use, a continuous metallic conductor for such purpose, even though highly flexible, is eventually subject to breakage due to fatigue of the metal. Or if a continuous metallic conductor is used of sufficient dimensions to insure durability, the vibratory characteristics of the horn will be seriously interfered with. On the other hand, the cooperating contacts 35 and 36 are made to have a substantially rocking and wiping engagement to give a permanent connection without affecting the vibration of the diaphragms or the tone characteristics of the horn in any objectionable manner. These contacts are kept clean and serviceable by the wiping action.

The core members 26 and 27 may be energized by a coil 40 secured to the face of core member 26 as by lugs 41 and 42. The lug 41 may be fastened to the diaphragm 14 as by a screw 43, and the lug 42 may be secured to the disc 26 as by a screw 44.

One of the terminals of the coil 40 may be brought out and clamped in electrical contact with the strip 37 by the binding screws 38. The other terminal of the coil may be likewise secured in contact with a contact supporting member 45. These connections may be made and insulated in a conventional manner, as best indicated in Fig. 6. A yielding contact supporting strip 46 may extend from the region of these interrupter parts to a binding post 47 similar to the binding post 33 above described, and connected and supported in a similar manner. A pair of non-deteriorating interrupter contacts 48 and 49 may be mounted respectively upon the contact supports 45 and 46. These contacts are preferably actuated conjointly by the vibratory movement of the two diaphragms 14 and 15, and for this purpose an interrupter controlling screw 50 may be threaded through the diaphragm 15 and discs 32 and provided at its inner end with an insulating piece 51 for engagement with the contact supporting strip 46. The contact 48 is sub-

stantially rigidly supported to vibrate with the diaphragm 14, and the contact 49 as supported by the member 46 is thus caused to move concurrently with the vibration of the diaphragm 15 by reason of the engagement of the piece 51 with the support, and thus the conjoint action of the opposed vibratory movements of the two diaphragms 14 and 15 serve to give a greater relative movement to the interrupter contacts, and such movement being controlled conjointly by the two diaphragms, will be kept approximately in step therewith, notwithstanding the slightly different vibratory characteristics.

15 The screw 50 may be provided with a lock nut 52 and the position of the screw may be readily adjusted through the outlet of the housing chamber to effect desired adjustment of the interrupter. The lock nut 20 may be held in place by a sheet metal member 52a having portions embracing the edge of the discs 32, and also the side of the nut 52, as shown, thus retaining the nut against loosening.

25 To secure a wide range of adjustment of the sound and tone characteristics of the horn, means are also provided for adjusting the air gap between the core members 26 and 27. Such means may take the form of an 30 adjustable core piece 53 mounted upon a screw member 54 threaded through the laminated core member 27 and extending to an accessible position in the sound outlet. By turning the screw 54 in or out, the air gap 35 in the magnetic field may be correspondingly varied between wide limits with a consequent variation in the natural frequency of vibration of the parts. The screws 50 and 54 may be adjusted conjointly during operation of the horn to secure a variety of effects 40 and to secure a high efficiency.

In the manufacture of diaphragms such as 14 and 15 by stamping operations, there will ordinarily be variations of several thousandths of an inch in the width of the flange portion 16, due perhaps to minor variations in thickness or other characteristics of the steel used. However, such variations may be readily compensated for by the adjustable air gap 50 as above described, so that the final effective air gap may be such as to give the horn a predetermined tone. Furthermore, the adjustable air gap renders unnecessary any of the refinements of manufacture which might 55 otherwise be necessary to secure substantially absolute uniformity of parts.

As to constructional features which are not herein specifically described in full, the specification of the copending application of Ralph O. Hood, Serial No. 12,423, filed February 28, 1925, "Acoustic signalling devices", may be followed, if desired. It will be understood that this invention, according to certain of its 60 phases, is applicable to acoustical devices gen-

erally, as well as to warning horns such as used on vehicles.

While the invention has been described in detail with respect to a particular preferred example thereof which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent of the United States is:

1. An electro-magnetic structure comprising highly vibratory members, a plurality of electric current leads mounted upon a relatively fixed support, and means for electrically connecting said leads to the actuating means of the vibratory structure comprising a plurality of pairs of cooperating spring pressed abutting contacts.

2. An electro-magnetic structure comprising highly vibratory members, a plurality of electric current leads mounted upon a relatively fixed support, and means for electrically connecting said leads to the actuating means of the vibratory structure comprising a plurality of pairs of cooperating spring pressed abutting contacts, one of said pairs of contacts comprising a circuit interrupter operated by the vibratory parts.

3. An acoustical signalling device comprising a pair of opposed vibratory diaphragms, electro-magnetic actuating means therefor mounted to vibrate therewith, and means for conducting current from a fixed terminal to said vibratory parts comprising a pair of cooperating spring pressed abutting contacts, in substantially continuous electrical contacting relationship, notwithstanding the vibration of the parts.

4. An acoustical signalling device comprising a housing chamber, a vibratory diaphragm structure and electro-magnetic operating parts therefor mounted within said chamber in spaced relation to the walls thereof, and a conductor terminal and binding post member rigidly secured to a non-vibratory part of said vibratory structure and extending therefrom out through the wall of said chamber.

5. An acoustical signalling device comprising a pair of complementary vibratory diaphragms joined together at their peripheries and forming an enclosure for receiving an electro-magnetic actuating means, a housing chamber enveloping said enclosure and with its walls spaced therefrom, a conductor terminal and binding post member rigidly secured to the joined peripheries of said diaphragms and extending therefrom through the wall of said chamber to the exterior there-

of, and an electrical connection from said member running to said actuating means.

6. An electro-magnetic signalling device comprising a vibratory diaphragm, an actuating coil and pole piece mounted at the center thereof, a group of interrupter parts rigidly secured in respect to said pole piece, and common means for clamping said parts and said coil in respect to the diaphragm.
- 10 7. An electro-magnetic signalling device comprising a relatively flat substantially circular housing chamber formed of two parts joined at their peripheries, a pair of complementary vibratory diaphragms joined at their peripheries, electro-magnetic actuating means within the enclosure formed by said diaphragms, said diaphragms being substantially circular and arranged coaxially with said chamber, but spaced from the walls thereof, and supporting posts secured to the joined peripheries of said diaphragms, certain of said posts being secured to one of said housing parts and others to the other housing part.
- 15 25 In testimony whereof I have signed my name to this specification.

CERTIFICATE OF CORRECTION.

Patent No. 1,794,308.

Granted February 24, 1931, to

HENRI L. MARINDIN.

It is hereby certified that error appears in the printed specification of the above numbered patent requiring correction as follows: Page 2, line 106, for "disc 26" read diaphragm 14; and that the said Letters Patent should be read with this correction therein that the same may conform to the record of the case in the Patent Office.

Signed and sealed this 17th day of March, A. D. 1931.

(Seal)

M. J. Moore,
Acting Commissioner of Patents.
